UNITED STATES PATENT OFFICE.

GEORGE C. EHRRBAR, OF CLEVELAND, OHIO.

FURNACE GRATE.

Application filed June 29, 1921. Serial No. 481,290.

To all whom it may concern:

Be it known that I, GEORGE C. EHRRBAR, a citizen of the United States, residing at Cleveland, in the county of Cuyahoga and 5 State of Ohio, have invented certain new and useful Improvements in Furnace Grates, of which the following is a specification.

This invention relates to improvements in fire grates.

10 The object of this invention is to provide a grate that will burn fuel with a maximum of efficiency.

More particularly the objects of the present invention are to provide means for 15 burning fuel in such a manner that the gases generated will be consumed as they are released and the ash and cinder residue reduced to a minimum.

Other objects will be apparent from the 20 following description and claims when considered in connection with the accompanying drawings.

Referring to said drawings, Fig. 1 is a plan view of an assembled grate.

25 Fig. 2 is a vertical longitudinal section on line 2—2, of Fig. 1.

Fig. 3 is an elevation of one of the grate bars.

Fig. 4 is a vertical cross section on line 30 4—4, of Fig. 1.

Fig. 5 is a vertical cross section on line 5—5, of Fig. 1.

The fire grate indicated at 6 comprises 35 interchangeable top bars 7, spaced apart by bars 8, which have deep webs or walls 8^a extending downwardly to engage the sides of interchangeable bars 9. The top surface of bars 9 lie in a plane substantially lower than the plane of the top of bars 7 and 8, 40 forming a depression 10 as shown in the drawings. The bars 7 are composed of longitudinal V-shaped ribs 7^a re-enforced by middle cross webs 7^b and terminating in end blocks 7^c. The sides of webs 7^b and ends

45 7^c form spacing lugs and are adapted to butt, the spaces between ribs 7^a forming slots 7^d. The bars 9 are similar to bars 7, having V-shaped ribs 9^a, re-enforced by webs 9^b and terminating in end blocks 9^c the 50 sides of webs 9^b and ends 9^c being adapted to butt, forming slots 9^d between the ribs 9^a. A portion of the slots 9^d may be filled by webs 9^e connecting the tops of ribs 9^a, forming a closed bar for purposes 55 hereinafter described. The bars 8 are composed of a V-shaped rib 8^a, similar to ribs

7^a and 7^b, connected by re-enforcing webs 8^b and ends 8^c to a vertical wall on deep rib 8^e, the space between forming slots 8^d. Lugs 8^f on walls 8^e are adapted to butt 60 against the sides of ends 9^c and webs 9^b and 9^e and space the ribs apart.

The ends 7^c and 8^c of bars 7 and 8 are supported by cross angle irons 11 and the bars 9 are supported by cross angle irons 65 12. The angle irons 11 and 12 are secured to the brick work of the furnace in any suitable manner.

To start the fire, coal is piled on the clean 70 grate and kindling or other suitable inflammable materials are placed on top and ignited. The coal is ignited by the burning kindling at the top and sides of the pile, combustion proceeding downwardly. The process of combustion is accelerated or retarded by the air draft which passes upwardly through slots 7^a, 8^a and 9^a in the 75 grate, through the fuel pile, and escapes through the boiler flue. Where the depth of the fuel pile is shallow, as along the edges, 80 the resistance offered to the passage of the draft will be slight, thereby causing the coal to burn more freely than at the middle over depression 10, where the passage of the draft upwardly is obstructed more by the greater 85 depth of coal, thereby reducing the draft and retarding combustion at the middle part of the grate.

With the fire burning downwardly and toward the middle of the coal bed and the 90 air draft passing upwardly, no gases will be generated other than those at the point of combustion, said gases being consumed as they are generated and released, none escaping and wasting, thereby increasing the efficiency of the fire. Furthermore, the coal 95 will be thoroughly burned, reducing the ashes and clinkers to a minimum.

Portions of slots 9^d in grate bars 9 in depression 10 may be closed by webs 9^e to 100 further obstruct combustion in said depression 10 at a point nearest to the flue, counteracting the pull of the draft which is strongest at that point, thereby distributing the progress of combustion evenly as desired. 105 The depth and width of depression 10 is varied to suit the furnace requirements.

The above described grates are simple in construction with parts removable and interchangeable at a small cost, and can be manufactured and sold at low price. 110

Other features of the invention will be

apparent to those who are skilled in the art to which it relates.

I claim:

A furnace grate comprising side sections 5 and an intermediate section therebetween, each side section consisting of spaced bars provided with spacing lugs at the ends and the middle thereof, the intermediate section being depressed thruout its entire length 10 below the level of the side sections and consisting of bars having depending cross webs 9^b at the middle thereof, that part of the

bars in front of said webs being spaced apart, and that part of the bars in the rear of said webs having laterally extending tops 15 9^e meeting to form a closed rear part of said intermediate section.

In testimony whereof, I do affix my signature in presence of two witnesses.

GEORGE C. EHRBAR.

Witnesses:

JOHN A. BOMMHARDT,
BESSIE F. POLLAK.
